Primary Examiner — Cary M Robinson*Assistant Examiner* — Emily Anna Saunders(74) *Attorney, Agent, or Firm* — Sam IP Legal Solutions, P.C.; Ryan D. Sam(57) **CLAIM**

The ornamental design for a game scoreboard and board rack, as shown and described.

DESCRIPTION

FIG. 1 is a top front perspective view of the game scoreboard and board rack showing my new design;

FIG. 2 is a bottom back perspective view thereof;

FIG. 3 is a front elevational view of the game scoreboard and board rack, wherein the back elevational view is a mirror image thereof;

FIG. 4 is a right side elevational view of the game scoreboard and board rack, wherein the left side elevational view is a mirror image thereof;

FIG. 5 is a top elevational view thereof; and,

FIG. 6 is a bottom elevational view thereof.

1 Claim, 5 Drawing Sheets(56)
